M. UNGER

ELECTRIC FURNACE

Filed March 12, 1924

Inventor:
Magnus Unger,

by *Alexander S. Gantz*
The Attorney

UNITED STATES PATENT OFFICE.

MAGNUS UNGER, OF PITTSFIELD, MASSACHUSETTS, ASSIGNOR TO GENERAL ELECTRIC COMPANY, A CORPORATION OF NEW YORK.

ELECTRIC FURNACE.

Application filed March 12, 1924. Serial No. 698,806.

To all whom it may concern:

Be it known that I, MAGNUS UNGER, a citizen of the United States, residing at Pittsfield, in the county of Berkshire, State 5 of Massachusetts, have invented certain new and useful Improvements in Electric Furnaces, of which the following is a specification.

My invention relates to electric furnaces 10 and has for its object the provision of improvements therein whereby greater current densities can be used in the molten charge and the rapidity of heating thereby increased.

15 My invention relates more specifically to electric furnaces of that type in which the charge is heated by means of a current passed through the charge. In electric furnaces of this type used in melting metals 20 there is a tendency for the liquid charge to be ruptured by the so called "pinch force" which is incidental to the passage of electric current through any conductor. This pinch force has the effect of squeezing or constricting 25 the conductor, and with a liquid conductor will rupture the circuit if the current density becomes high enough. When rupture occurs the action of the furnace is intermittent and otherwise unsatisfactory so that 30 the maximum permissible current density in the current carrying charge for satisfactory operation is limited to that density which will produce rupture. The power input and hence the rapidity of heating is thus limited by the pinch force.

It is well known that by increasing the hydrostatic head of the molten charge, the 35 pinch force is counteracted to some extent so that higher current densities can be used 40 whereby the rapidity of heating may be increased. This hydrostatic head may be obtained by providing a deep narrow channel for the charge. A narrow channel has the disadvantage, however, that it may not be satisfactorily recharged with pieces of the metal 45 to be melted of ordinary dimensions. To facilitate recharging a relatively wide channel is therefore desirable, but for rapid heating a deep, narrow channel is desirable.

50 In carrying out my invention I use a relatively wide channel provided with a deep narrow groove in the bottom whereby a hydrostatic head of metal may be produced to permit the use of higher current densities.

55 For a more complete understanding of my

invention reference shall be had to the accompanying drawing, the single figure of which is an elevation view partly in section of an electric induction furnace embodying my invention.

60 Referring to the drawing, I have shown my invention in one form as embodied in an electric furnace of the induction type although it obviously has application to various other furnaces in which the charge is 65 heated by current passed through the charge. This induction furnace comprises an annular member 10, made of suitable refractory material, provided with a horizontally disposed annular channel 11 for the charge 12. 70 The refractory member 10 is interlinked by an iron core 13 on which is mounted a primary winding 14. As shown, the winding 14 is concentrically arranged with respect to the refractory channel member 10. It will 75 be understood that the charge 12 in the channel forms a closed secondary conductor for a transformer of which the coil 14 is the primary winding.

80 In accordance with my invention I provide a relatively deep narrow groove 15 in the refractory 10 at the bottom and forming a part of the channel 11. This groove serves to increase the hydrostatic head of metal in the channel, that is, it increases its 85 depth so as to counteract the pinch force to some extent. It will be observed that the groove, being relatively narrow, does not materially increase the capacity of the channel. The effect of the groove is particularly 90 advantageous after a heat has been poured when only a small amount of metal is left in the channel. In such case the hydrostatic head of molten metal due to the groove 15 permits the use of greater current 95 densities in melting the fresh charge than would be possible were this small amount of molten charge distributed in a shallow pool over the relatively flat bottom of a wide channel. Also, it will be observed that with this arrangement the channel 11 can be made any convenient width to receive relatively 100 large pieces in recharging and also to facilitate the handling of slag.

105 While I have described my invention as embodied in concrete form and as operating in a specific manner in accordance with the provisions of the patent statutes, it should be understood that I do not limit my invention thereto, since various modifications 110

thereof will suggest themselves to those skilled in the art without departing from the spirit of my invention, the scope of which is set forth in the annexed claims.

5. What I claim as new and desire to secure by Letters Patent of the United States is:

1. An electric furnace comprising a crucible providing a relatively wide channel in which the charge is heated by current passed therethrough, said channel including a relatively deep narrow groove at the bottom for increasing the hydrostatic head of molten metal.

18. An electric furnace comprising a crucible provided with a channel for the charge, said channel having a relatively wide top portion, and a relatively deep narrow bottom portion for increasing the hydrostatic head of molten metal, and means for producing flow of heating current through the charge.

20. An electric induction furnace comprising a crucible providing a relatively wide looped channel in which the charge constitutes a closed secondary, said channel including a relatively narrow groove at the

bottom for increasing the hydrostatic head of molten metal.

4. An electric induction furnace comprising a horizontally disposed annular crucible providing a relatively wide looped channel in which the charge forms a closed secondary, said channel including a relatively deep narrow groove at the bottom for increasing the hydrostatic head of molten charge, a core interlinking said channel, and a primary winding on said core for inducing heating currents in said secondary.

5. An electric furnace for melting metals comprising a crucible providing a channel in which the charge is heated by a current passed through the charge, said channel being relatively wide to receive large pieces of metal to be melted and being provided with a relatively narrow groove at the bottom for increasing the hydrostatic head of molten metal without appreciably increasing the capacity of said channel.

In witness whereof, I have hereunto set my hand this eighth day of March, 1924.

MAGNUS UNGER.
